UNITED STATES PATENT OFFICE

ROY BLAIR EVERSON, OF CHICAGO, ILLINOIS, ASSIGNOR TO THE EVERSON FILTER COMPANY, OF CHICAGO, ILLINOIS, A CORPORATION OF ILLINOIS

SUBMARINE LIGHTING FIXTURE

Application filed January 31, 1929. Serial No. 336,377.

This invention is intended primarily for use in association with swimming pools; or display fountains and the objects of the present invention are to provide a submerged lighting element whereby the sides, the bottom of the pool, and the swimmers' bodies at all positions in the pool may be brightly lighted, and lighted without noticeable differences in the intensity of illumination.

10 Another object of this invention is to provide a lighting element so designed as to prevent the direct glare of the reflected light rays from interfering with the swimmers in the pool; and further to protect the eyes of 15 the observers from a reflected glare from the surface of the water.

A further object is to provide a means for employing colored lights to tint the water of the pool or fountain to any desired color 20 or color effect.

A still further and important object is to provide means to eliminate the now present and objectionable feature of the glass breaking in the lighting element.

25 And a still further object of this invention is to provide a structure economical to manufacture and one that is easily installed in the present designs of swimming pool and fountain construction, and one that is readily accessible for repairs and adjustment after installation.

Although this invention is primarily intended for the purpose above stated, it is obviously applicable for uses in connection with 35 various other types of under water illumination where similar conditions are encountered.

In the accompanying drawings Fig. 1 is a 40 sectional view of the submarine lighting fixture assembled in the wall of a swimming pool; Fig. 2 is a front elevation partially in section of Fig. 1; and Fig. 3 is a sectional elevation of a modified construction of the details shown at Figure 1.

45 The numeral 1 represents the body or wall of a swimming pool of standard construction, preferably concrete, which is faced on the inner side with a finish of concrete 2, or this finish may be of tile as is also very commonly 50 used.

My invention consists in providing an annular flat ring 3, with integral anchors, being cast into the wall of the pool at the time the wall is poured. To this ring 3, is fitted a jacketed container comprising an inner wall 4, and an outer wall 5; which walls are flanged at their respective ends and are bolted or otherwise fastened to a rear plate 6, serving to seal the rear face of the water-jacket so formed. The opposite flanged ends of the members 4 and 5 are also sealed with a ring 7, which is provided with apertures 8, which permit the water of the pool entering the jacket formed by the members 4 and 5, and to circulate around the member 4, so that the cold water coming in at the bottom will circulate upwards and out the top aperture 8a, as will be hereinafter described. The rear plate 6, is provided with a plurality of set screws 9, and lock nuts 10, which are tapped through the plate 6, and have bearing against the rear face of the wall 1, so that when the set screw is tightened against the rear face of the wall, the plate 7, is tightened against the outer or front face of the ring 3, forming a 75 water tight seal.

The water jacketed container comprising the walls 4 and 5 with the rear and front plates 6 and 7, is adapted to carry a lighting element by means of a bracket 11, being secured to the plate 6. This lighting element for sake of description is shown on the drawings and comprises a standard light socket 12, reflector holder 13, reflector 14, and lamp 15. The lighting element, as a unit being 85 made adjustable on the rear bracket by means of the lock nuts 16 and 17, and the washers 18 and 19.

On the inner wall of the ring 4, are interposed lugs 20 and 21, against which is placed a lens, a light filter or light diffusing element 22, which is held in place by the clip springs 23. By means of the lug 20, and an additional lug 24, a second lens 25, preferably corrugated, frosted, or clear and which is held in place by means of the outer ring 7, with an integral lip 7a, bearing against the face of the lens 25, and making a water tight connection, either by means of a washer or waterproof cement 26, interposed between the lip 100

7a, and the lens 25, as shown in Fig. 1, in the drawing. This glass may be carried by a separate element such as a ring 30, as shown at Fig. 3, of the drawings.

On the water side or front wall of the lighting unit is the lens 25, which as above stated is preferably of corrugated glass which tends to spread the light rays laterally, whereas the inner lens 22, is adapted to either filter or color the light, and to direct the light rays from the lighting element itself in the form of a pencil or sheet upon the surface of the lens 25. The axis of the lamp and reflector, and preferably the inner plate 22, is so adjusted as to point downwardly to a location approximating the junction of the opposite side wall of the pool with the bottom of the pool. The mounting of the lamp socket is adjustable as before described, so that each unit of the many comprising a complete installation for a pool, while of identical construction, may be adjusted after installation to give the correct light distribution relative to its particular location in the pool.

The front lens 25, being in contact with the water will vary in temperature through a limited temperature range, although considerable heat will be generated by the lamp 15, in its operation. This temperature change ordinarily would be characterized by considerable expansion and contraction of the lens 25, and to eliminate this I have provided the water jacket which permits the water of the pool to circulate around the support of the lens and thus carry off the heat generated by the light and transmit it to the water of the pool.

Having thus described my invention, what I claim as new and desire to secure by Letters Patent is:

1. In a submarine lighting fixture, the combination of an annular water-jacketed container, a lighting element mounted therein, a lens supported transversely of and by the walls of said water-jacketed container, means for sealing said lens in place, a light filter interposed between said lighting element and said lens, and means for securing said light filter in a plane at an angle to said first mentioned lens.

2. In a submarine lighting fixture, the combination of an annular ring, an annular water-jacketed container mounted therein, a lighting element adjustably supported therefrom, a lens supported transversely of and by the walls of said water-jacketed container, means for sealing said lens in place, a light filter interposed between said lighting element and said lens, means for securing said light filter in a plane at an angle to said lens, and means for sealing said container against said first mentioned annular ring.

ROY BLAIR EVERSON.
